UNITED STATES PATENT OFFICE.

DAVID LEWIS WALMSLEY AND CATHERINE WALMSLEY, OF DETROIT,
MICHIGAN.

DESIGN FOR A TOOTH BRUSH AND POWDER RACK.

SPECIFICATION forming part of Design No. 31,028, dated June 20, 1899.

Application filed May 18, 1899. Serial No. 717,385. Term of patent 14 years.

To all whom it may concern:

Be it known that we, DAVID LEWIS WALMSLEY and CATHERINE WALMSLEY, citizens of the United States, residing at Detroit, in the county of Wayne and State of Michigan, have invented and produced a new and original Design for a Tooth Brush and Powder Rack; and we do declare the following to be a full, clear, and exact description of the same, reference being had to the accompanying drawing, forming a part thereof.

This invention relates to the toilet, and more especially to racks such as may be attached to walls or wherever desired.

15 The object of the same is to produce an original design of tooth-brush and toilet racks.

In the accompanying drawing is shown a general perspective view of this device complete.

20 As shown in the drawing, the leading and most striking feature of our design is the back, provided with a series of cups, three in number, described below; but the device possesses other features, which are also ornamental, 25 such as the shelf and hooks.

Referring by letter to the drawing, A designates the back or upright, near each end of which is a series of eyes B. Near the bottom and at the center of the back A is a horizontal shelf C, having a raised and ornamental 30 front D, while the body of the shelf is perforated, as seen. Just above the shelf two or more hooks E project from the back, as shown. Occupying a position near the top of the back and above the shelf are three cups. 35

Having thus described our invention, what we claim as new, and desire to secure by Letters Patent, is—

The design for a tooth-brush and toilet rack herein shown and described. 40

In testimony whereof we affix our signatures in presence of two witnesses.

DAVID LEWIS WALMSLEY.
CATHERINE WALMSLEY.
